UNITED STATES PATENT OFFICE

133,690

DESIGN FOR A MONUMENT

Oliver Wilbert Anderson, Cedar Rapids, Iowa

Application May 26, 1942, Serial No. 107,011

Term of patent 3½ years

To all whom it may concern:

Be it known that I, Oliver Wilbert Anderson, a citizen of the United States, residing at Cedar Rapids, in the county of Linn and State of Iowa, have invented a new, original, and ornamental Design for a Monument, of which the following is a specification, reference being had to the accompanying drawing, forming part thereof.

The figure is a front perspective view of a monument, showing my new design. The back of the monument is substantially a duplicate of the front.

I claim:

The ornamental design for a monument, as shown and described.

OLIVER WILBERT ANDERSON.
